United States Patent Office.

DAVID K. HOXSIE, OF PROVIDENCE, RHODE ISLAND.

Letters Patent No. 74,758, dated February 25, 1868.

IMPROVED IMPLEMENT FOR MAKING EYELETS.

The Schedule referred to in these Letters Patent and making part of the same.

TO ALL WHOM IT MAY CONCERN:

Be it known that I, DAVID K. HOXSIE, of the city and county of Providence, and State of Rhode Island, have invented certain new and improved Instruments or Tools for Making Eyelets; and I do hereby declare that the following is a full, clear, and exact description of the same, reference being had to the accompanying drawings, making part of this specification, in which—

Figure 1 is a longitudinal view and section of my improved eyelet-instruments or tools.

Figure 2 represents the various stages of the operation of making eyelets with my said instruments or tools.

Figure 3 represents said instruments in the act of performing their respective operations.

Similar letters or numbers indicate like parts in all the figures.

My improved eyelet-instruments are calculated to make an eyelet from a planchet or disk of sheet metal, by first converting the planchet into a tube, with one closed end, and then cutting out the closed end, and expanding that edge of the tube to form the flange. My invention for this purpose consists—

First, of a movable forming-punch, with a bevelled end, and a cavity in the end, forming thereby a sharp concentric edge, for centring and confining the punch to the centre of the planchet, so that it will be drawn evenly upon the cylindrical end of the punch.

Secondly, my invention consists of a stationary die, with an entrance of suitable diameter to receive a planchet of the requisite size to form an eyelet; a drawing-cavity beneath, of a conical form, (or nearly so,) for gradually contracting and drawing the periphery of the planchet upon the cylindrical part or end of the punch, above mentioned, with a contracted throat below, for drawing the contracted planchet into a tube around the punch; and an expanding-cavity at the rear of the die, to shape the flange of the eyelet after the closed end of the tube is cut out by suitable means.

Thirdly, my invention consists of a movable concentric cutting-punch or tube, for cutting out the closed end of the tube on the punch at the rear of the die, and a bevelled edge, for expanding and turning over the severed edge of the tube into the cavity at the rear of the die, to form the flange on the eyelet.

To enable others skilled in the art to make and use my invention in accordance with the mode which I have adopted and embodied therein, I will proceed to describe the same.

In the drawings, No. 1 represents the movable forming-punch, No. 2 the stationary die, and No. 3 the movable cutting-punch, above referred to.

The forming-punch, No. 1, it will be observed, is cylindrical near the end, at e , bounded by a square shoulder, i , such cylindrical portion corresponding with the length and bore of the proposed tube which is to be made, for after-conversion into an eyelet. The end of this punch (No. 1) is bevelled at a ; and in the end there is a centre or cavity, t , which, with the bevelled end, forms a sharp concentric edge, which, when pressed against the planchet (of softer metal) as it is held at the entrance of the die, penetrates the metal sufficiently to prevent it from departing from its central position with respect to both punch and die, and insures an even and uniform drawing of the metal on all sides around the said punch, and, in consequence, the formation of a perfect tube. The punch, No. 1, is intended to be inserted and operated in the plunger of a power-press, such as is generally used by jewellers and others in forming like shapes of sheet metal.

The die, No. 2, is intended to be stationary, and is secured in the bed-piece of a similar power-press; and it will be observed that said die has a circular entrance, n , calculated to receive a planchet or disk of metal; also that, below this entrance-end, there is a conical drawing-cavity, s , which is contracted into a throat, x ; corresponding in diameter to that of the exterior of the proposed tube, which throat finally expands into a cavity, r , at the rear of the die, corresponding to the shape of the flange of the proposed eyelet, said throat x and cavity r constituting an eyelet-forming die at the rear or bottom of the drawing-part of the die; but, inverted from the position, such eyelet-forming part is placed in all other dies for making eyelets heretofore in use or known.

The movable cutting-punch, No. 3, it will be seen, is tubular; and this is intended to be operated in a plunger working at the rear of the die, and similar, in all respects, to that which operates the punch No. 1. The bore of this tubular punch (No. 3) corresponds with and fits upon the end of punch No. 1. The end is

bevelled at g , and forms a sharp concentric cutting-edge on the extreme end, at c , so that, when it is pressed against the closed end of the eyelet, in the manner shown in the "third operation" of fig. 3, the closed end of the tube will be cut out, and be deposited within the bore of the cutter, and, at the same time, the bevelled end of the cutting-punch will expand the severed edge of the tube against the surface of the cavity at the rear of the die, and thus form the flange upon the eyelet-tube, as shown in fig. 2, No. 4, the first operation of the said instruments, as shown in fig. 3, being to deposit and press the planchet into the drawing-cavity s of the die, the "second operation" being to push the planchet through the throat x of the die, and convert it into a tube with a closed end, which protrudes from the rear of the die, convenient to have the "third operation" performed upon the closed end by the cutting-punch, No. 3, in the manner shown.

Having described my invention, what I claim, and desire to secure by Letters Patent, is—

1. The movable forming-punch, No. 1, constructed with a cylindrical shape or former, e , a shoulder, i , a bevelled end, a , and a centre cavity, t , when combined with mechanism so as to operate substantially as described, for the purpose specified.
2. I claim the stationary die, No. 2, constructed with a circular entrance, n , a conical drawing-cavity, s , a throat, x , and an expanding-cavity, r , at the rear, when combined with mechanism so as to operate substantially as and for the purpose specified.
3. I claim the movable cutting-punch, No. 3, constructed in a tubular form, with a bevelled surface, g , and a concentric cutting-edge, c , when combined with mechanism, such as herein described, so as to operate substantially as and for the purpose specified.
4. I claim the method, herein described, of forming an eyelet, by first converting a planchet or disk of metal into a tube with a closed end, and then cutting out the closed end, and expanding this severed edge of the tube, to form the flange, by means substantially as described.
5. I claim so combining a drawing-punch and an open drawing-die, constructed substantially as described, that the planchet of metal from which the eyelet is to be made will enter in at the front end of the die, and, passing through, be delivered completely formed into an eyelet at the rear end of the die, substantially as described.

DAVID K. HOXSIE.
